UNITED STATES PATENT OFFICE.

GEORGE W. WYMAN, OF WILMINGTON, DELAWARE.

LOCOMOTIVE DRIFTING DEVICE.

1,212,726.

Specification of Letters Patent. Patented Jan. 16, 1917.

Application filed April 19, 1916. Serial No. 92,120.

To all whom it may concern:

Be it known that I, GEORGE W. WYMAN, a citizen of the United States, residing at Wilmington, in the county of New Castle and State of Delaware, have invented a certain new and useful Improvement in Locomotive Drifting Devices, of which the following is a specification.

The invention relates to devices for permitting a limited supply of steam to flow to the steamchests and cylinders of the locomotive when the throttle-valve is closed and the engine is drifting. By this introduction of steam the formation of a vacuum in the cylinder and chest is avoided, the desired lubrication is insured and carbonizing is prevented. It is generally recognized that such auxiliary supply is desirable in all types of locomotives and especially in engines using superheated steam. It is also desirable under certain conditions that such supply shall cease when the locomotive is stopped, thus preventing a possible accumulation of pressure in the cylinders, but is mainly of advantage in avoiding the escape of steam around the valve stems and piston rods, or other leakage, while the locomotive is at rest.

The object of this invention is to provide automatically operated means whereby the required limited quantity of steam is supplied to the valvechests and cylinders while drifting, and such supply is cut off when the locomotive is stopped.

The invention consists in certain novel features of construction and arrangements of parts, by which the above objects are attained, to be hereinafter described and claimed.

The accompanying drawings form a part of this specification and show an approved form of the invention.

Figure 1 is a side elevation showing the application of the invention to a locomotive. The latter is only partially shown. The succeeding figures are on a larger scale. Fig. 2 is a vertical longitudinal section showing the valve mechanism for controlling the auxiliary steam supply. Fig. 3 is a corresponding elevation at a right angle to the preceding figure, and partly in vertical section. Fig. 4 is a horizontal section taken on the line 4—4 in Fig. 2. Fig. 5 is a vertical section taken on the line 5—5 in Fig. 2, and partly in elevation. Fig. 6 is an elevation showing certain piston valves and their connections.

Similar letters of reference indicate the same parts in all the figures.

Referring to Fig. 1, A is the boiler of a locomotive, shown by the dotted lines as 60 having a dry-pipe B joined to the header C of a superheater, and having steam pipes as D, leading from the superheater to the steam chests D¹ and cylinders D². All these parts may be of any approved type. 65

At the rear of the boiler within the cab is a connection A¹ which may be the usual turret or bridge, from which extends a pipe L leading to a valve mechanism to be described, and thence through the pipe M to the header C at any desired or convenient point thereon or to any connection through which steam may be led to the steamchest D¹ and cylinder D². By connecting to the header C of the superheater, auxiliary steam 75 is supplied to both sides of the locomotive through the one pipe M. Admission of saturated steam from the boiler to the pipe L is controlled by a valve L¹ in the cab.

The valve mechanism for automatically controlling the auxiliary flow of steam through the pipes L and M to the valve-chests and cylinders is contained in a casing F introduced alongside the boiler near the front, between the pipes L and M by any 80 suitable couplings, and has a vertical extension F¹ on which is a bonnet F⁵. The casing F has a diaphragm or partition F² in which is a valve-seat F³ for a vertically movable check-valve G mounted in axial alignment 85 with the extension F¹ and bonnet F⁵, and between the valve-seat F³ and pipe M, in the chamber f¹ is a valve-seat F⁴ adapted to receive a horizontally movable checkvalve H. The valve G is arranged to shut off communication 90 from the pipe L through the passage f and valve-seat F³, and the checkvalve H is arranged to shut off communication between the space below the valve-seat F³ and pipe M. 95

The valve H matches to the horizontal chamber or cylinder f¹ in which it is mounted and has a packing-ring H¹. The valve H is guided by a stem H² received in the central boss of a spider-frame H³ which 105 also serves as a stop to limit the outward movement of the valve. At the outer end of the chamber f¹ are by-passes or ports f² formed in the casing and adapted to permit steam to flow from one face of the valve H 110 to the other when the latter is in its outward position, and pass to the steam-chest.

The vertical valve G has a stem G¹ extending upwardly and carries at its upper end a piston J movable vertically in the cylinder j in the bonnet F⁵ in unison with the movements of the valve G. The latter is also fitted piston-wise in its chamber g above the valve-seat and separated from the cylinder j by a horizontal disk K through which the valvestem G¹ passes.

10 In the wall of the extension and bonnet is a vertical steam passage j² leading steam from the passage f through an inlet port j³ to the cylinder j, and on the opposite side of the bonnet is an exhaust passage j⁴ in communication with the cylinder j through the ports j⁵ j⁶ and to the atmosphere through the port or opening j⁷ in the cylinder j between the horizontal check-valve G and the under face of its piston J. The thickness of 20 piston J is such, and the inlet port j³ and exhaust ports j⁵, j⁶ are so located relatively thereto, that when the piston is down, as shown in full lines in Fig. 2, and the valve G is seated, the inlet port j³ is open and the 25 lowermost exhaust port j⁶ is closed permitting steam from the boiler to fill the passages j² j⁴ and the cylinder j above the piston; and when the piston is raised to the position shown in dotted lines in Fig. 2, the 30 inlet port is covered and both exhaust ports uncovered, permitting the steam imprisoned above the piston to flow through the port j⁵ passage j⁴ and port j⁶ to the space below the piston whence it escapes freely through the 35 opening j⁷ which is always open to the atmosphere.

N is a spring encircling the stem G¹ and abutting against the disk K, serving by its slight expansive force against the piston J 40 to lift the valve G from its seat and also to cushion the valve in its seating movement. The spring N is inclosed and guided in a sleeve N¹ on the disk K.

P is a plunger mounted to move vertically 45 in a plug P¹ screwed centrally into the top of the bonnet F⁵ and containing a spring P² abutting at one end against a collar P³ on the plunger and at the other against an adjustable screw cap or follower P⁴ on the plug, and exerting its force to hold the plunger yieldingly downward with its lower end projecting axially through the plug P¹. The plunger receives the impact of the piston 50 on its upward movement and the force thus stored in the spring P² serves to initiate the downward movement of the piston J and valve G, as will appear.

On the inner face of the horizontal check-valve H is an arm or extension H⁴ having 60 an inclined face h adapted to strike against and coact with a downwardly extending pin G² on the valve G and lift the latter as the valve H approaches its seat F⁴ and hold the valve G and its connected piston J in the elevated position until the outward move-

ment of the valve H permits the pin G² again to ride down the beveled face h of the arm H⁴. A ball G³ loosely mounted at the lower end of the pin G² serves as a roller to reduce the frictional contact of the pin and arm. The latter is shown as rectangular in face view and is guided in a corresponding notch f³ in a boss F⁶ formed on the interior of the casing F. This engagement with the notch prevents rotation 75 of the arm and insures proper presentation of the beveled face to the ball G³. The inlet port j³ from the passage j² is controlled by a screw J¹ by which the effective area of the port may be varied.

80 It will be seen that the inward movement of the valve H raises the valve G from its seat and permits steam to flow from the pipe L through the valve-seat F³, and at the same time raises the piston J to cover the inlet port j³ and open the exhaust ports j⁵ j⁶.

85 The operation may be briefly described as follows:—When the locomotive is running normally with the throttle open, the pressure in the steam pipe D acting through the pipe M on the large area of the horizontal check-valve H forces the latter to its seat thus shutting off communication through the pipes L and M, and by the action of the inclined face h on the pin G² holds the vertical 90 checkvalve G and its piston J in the elevated position with the inlet port j³ covered, as 95 shown in dotted lines in Fig. 2.

90 When the throttle is closed, as when the engine is drifting, the pressure in the pipes 100 D and M falls and steam from the boiler through the pipe L and valve-seat F³ acting upon the inner face of the valve H forces it outwardly to the position shown in full lines in Fig. 2, while the vertical check-valve G is held in the partially elevated position by the spring N and steam flows freely 105 through the pipe L, valve-seat F³, chamber f¹, ports f² to the pipe M and thence to the steamchests and cylinders to supply the required volume of wet steam; the vertical 110 valve G is held from its seat by the slight force of the spring N although the inlet port is uncovered, for the reason that the idle reciprocations of the pistons in the cylinders 115 of the engine call for more steam than can be supplied through the pipes L and M and consequently draws from all sources, resulting in a reduction of pressure on the upper 120 face of the piston J below that required to force the piston downwardly against the opposition offered by the spring N and to seat the valve G. But as soon as the engine stops and the pistons no longer call for steam, pressure from the boiler through the pipe 125 L, passages f and j², and inlet port j³, builds up on the upper face of the piston J and forces the latter downward against the resistance of the spring N and seats the valve G, thus shutting off the auxiliary supply. It 130

will be noted that the area of the piston J is greater than that of the vertical check-valve G so that although the steam pressure acting upon the under face of the valve G is the same as that acting upon the upper face of the piston J, the greater area of the latter causes the valve G to be forced to its seat. The area of the horizontal checkvalve H is also considerably greater than that of the piston J, and as the valve H matches closely in its cylinder ¹ its outward movement is effected easily and positively. The inlet port ² and exhaust port ³ are so located that the former is covered by the piston J before the latter is uncovered, and when the exhaust port ³ is open, steam from above the piston escapes freely.

The spring P² serves as an aid to gravity in insuring the initial downward movement of the piston J far enough to uncover the inlet port ² as soon as the piston J and valve G are released by the withdrawal of the arm H⁴, but the spring P² and its plunger P may be omitted, relying upon the weight of the parts alone to induce the descent. Other modifications may be made in the forms and proportions of the parts, and in the relative arrangements of the checkvalves and several ports and passages in adapting the invention to various types of locomotives.

I claim:-

1. In a device of the character set forth, an auxiliary pipe leading steam from the boiler to the steamchest of an engine, a checkvalve in said pipe actuated by steam-chest pressure and adapted to close said pipe, a second checkvalve in said pipe actuated by boiler pressure and adapted to close said pipe, and means operated by the difference in such pressures for automatically closing one of said valves and opening the second when the engine is running, closing said second valve and opening the other when the engine is stopped, and holding both of said valves open when the engine is drifting.

2. In a device of the character set forth, an auxiliary pipe leading steam from the boiler to the steamchest of an engine, a checkvalve in said pipe subject to steam-chest pressure and arranged to seat in one direction and close said pipe, a second checkvalve in said pipe actuated by boiler pressure in said pipe and arranged to seat in the opposite direction and close said pipe, and means automatically operated by the difference in such pressures for closing one of said valves and opening the second when the engine is running, closing said second valve and opening the other when the engine is stopped, and holding both of said valves open when the engine is drifting.

3. In a device of the character set forth, an auxiliary pipe leading steam from the boiler to the steamchest of an engine, a checkvalve in said pipe subject to steam-

chest pressure and arranged to seat in one direction and close said pipe, a second checkvalve in said pipe of less area than the first, arranged to seat in the opposite direction and close said pipe, and actuated by boiler pressure in said pipe, and means actuated by the closing of said first checkvalve for opening said second checkvalve, and means operated by the difference in effective pressures on said valves for automatically closing the first of said checkvalves and opening the second when the engine is running, closing the second of said checkvalves and opening the first when the engine is stopped, and opening both of said checkvalves when the engine is drifting.

4. In a device of the character set forth, an auxiliary pipe leading steam from the boiler to the steamchest of an engine, a casing in said pipe having two oppositely arranged valves seats therein, a checkvalve on the steamchest side of said casing arranged to coact with one of said seats to close said pipe under steamchest pressure, a second checkvalve on the boiler side of said casing arranged to coact with the other of said seats to close said pipe and operated by boiler pressure, means actuated by the closing movement of said first checkvalve for opening said second checkvalve, yielding means for supporting said second checkvalve in the open position, and means subject to boiler pressure and acting in opposition to said yielding means for closing said second checkvalve.

5. In a device of the character set forth, a casing having a passage therethrough in communication at one end with a steam boiler and at the other with the steamchest of an engine, a vertically movable checkvalve arranged to close said passage from such boiler by a downward movement, a horizontally movable checkvalve arranged to close said passage to such steamchest by a movement toward said vertical valve, a piston carried by said vertical valve and movable vertically in a cylinder in said casing, said cylinder having exhaust ports, and an inlet port in communication with such boiler, said ports arranged to be opened and closed by the movements of said piston, and means carried by said horizontal valve for lifting said vertical valve and piston by the closing movement of said horizontal valve.

6. In a device of the character set forth, a casing having a passage therethrough in communication at one end with a steam boiler and at the other end with the steam-chest of an engine, a vertically movable checkvalve closing such passage from such boiler by a downward movement, a horizontally movable checkvalve arranged to close said passage to such steamchest by a movement toward said vertical valve, a piston carried by said vertical valve and movable

- vertically in a cylinder in said casing, said cylinder having exhaust ports, and an inlet port in communication with such boiler, said ports arranged to be opened and closed by the movements of said piston, a pin on said vertical valve extending through its seat, and an arm on said horizontal valve having an inclined face adapted to engage said pin and lift said vertical valve and piston by the closing movement of said horizontal valve.
7. In a device of the character set forth, a casing having a passage therethrough in communication at one end with a steam boiler and at the other with the steamchest of an engine, a vertically movable check-valve arranged to close said passage from such boiler by a downward movement, a horizontally movable checkvalve arranged to close said passage to such steamchest by a movement toward said vertical valve, a valve-stem on the latter, a piston mounted on said valve-stem, a disk in said casing between said vertical valve and piston, a cylinder in said casing receiving said piston, said cylinder having exhaust ports, and an inlet port in communication with such boiler, said ports arranged to be opened and closed by the movements of said piston, means carried by said horizontal valve for lifting said vertical valve and piston by the closing movement of said horizontal valve, and a spring on said disk arranged to hold said vertical valve yieldingly from its seat until forced thereto by pressure on said piston.
8. In a device of the character set forth, a casing having a passage therethrough in communication at one end with a steam boiler and at the other with the steamchest of an engine, a vertically movable check-valve arranged to close said passage from such boiler by a downward movement, a horizontally movable checkvalve arranged to close said passage to such steamchest by a movement toward said vertical valve, a valve-stem on the latter, a piston mounted on said valve-stem, a disk in said casing between said vertical valve and piston, a cylinder in said casing receiving said piston, said cylinder having exhaust ports, and an inlet port in communication with such boiler, said ports arranged to be opened and closed by the movements of said piston, means carried by said horizontal valve for lifting said vertical valve and piston by the closing movement of said horizontal valve, a spring on said disk arranged to hold said vertical valve yieldingly from its seat until forced downwardly by steam pressure on said piston, and a spring in said casing above said piston arranged to act upon said piston and initiate such downward movement.
9. In a device of the character set forth, a casing having a passage therethrough in communication at one end with a steam boiler and at the other with the steamchest of an engine, a vertically movable checkvalve arranged to close said passage from such boiler by a downward movement, a horizontally movable checkvalve arranged to close said passage to such steamchest by a movement toward said vertical valve, a piston carried by said vertical valve and movable vertically in a cylinder in said casing, said cylinder having exhaust ports, and an inlet port in communication with such boiler, said ports arranged to be opened and closed by the movements of said piston, an arm on said horizontal valve having an inclined face, a guide in said casing receiving said arm, a pin on said vertical valve projecting through its seat with its lower end in the path of said arm, said arm and pin arranged to serve in lifting said vertical valve by the closing movement of said horizontal valve.
10. In a device of the character set forth, a casing having a passage therethrough in communication at one end with a steam boiler and at the other with the steamchest of an engine, a vertically movable check-valve arranged to close said passage from such boiler by a downward movement, a horizontally movable checkvalve arranged to close said passage to such steamchest by a movement toward said vertical valve, a piston carried by said vertical valve and movable vertically in a cylinder in said casing, said cylinder having exhaust ports, and an inlet port in communication with such boiler, said ports arranged to be opened and closed by the movements of said piston, and means carried by said horizontal valve for lifting said vertical valve and piston by the closing movement of said horizontal valve, said piston having an area greater than said vertical valve, and said horizontal valve having an area greater than said piston.
11. In a device of the character set forth, a casing having a passage therethrough, two independently movable checkvalves controlling such passage, and means carried by one of said valves and operable in its closing movement, for opening the other of said valves.
12. In a device of the character set forth, a casing having a passage therethrough, two independently movable checkvalves controlling such passage, a cylinder in said casing, a piston carried by one of said valves and received in said cylinder, and means carried by the other of said valves and operable in its closing movement, for lifting said piston and its connected valve.
13. In a device of the character set forth, a casing having a passage therethrough, two independently movable checkvalves controlling such passage, a cylinder in said casing, a piston carried by one of said valves and received in said cylinder, means carried by the other of said valves and operable in its closing movement, for lifting said piston and its connected valve.

closing movement, for lifting said piston and its connected valve, and a spring serving to support yieldingly said piston and its valve when the latter is released by the withdrawal of such lifting means.

14. In a device of the character set forth, a casing having a passage therethrough, two independently movable checkvalves controlling such passage, a cylinder in said casing, 10 a piston carried by one of said valves and received in said cylinder, means carried by the other of said valves and operable in its

closing movement, for lifting said piston and its connected valve, a spring serving to support yieldingly said piston and its valve 15 when the latter is released by the withdrawal of such lifting means, and a spring in said casing serving to initiate the return movement of said piston and its valve when thus released.

20 In testimony that I claim the invention above set forth I affix my signature.

GEORGE W. WYMAN.
